UNITED STATES PATENT OFFICE

168,792

AUTOMOBILE COOLER

Theron L. Hedgpeth, Annapolis, Calif., assignor to
Carl Lynch, Kingman, Ariz.

Application January 22, 1952, Serial No. 18,144

Term of patent 14 years

(Cl. D14—6)

To all whom it may concern:

Be it known that I, Theron L. Hedgpeth, a citizen of the United States, residing at Annapolis, county of Sonoma, State of California, have invented a new, original, and ornamental Design for Automobile Cooler, of which the following is a specification, reference being had to the accompanying drawing, forming a part hereof.

Fig. 1 is a side elevational view of an automobile cooler showing my new design.

Fig. 2 is a side elevational view of the automobile cooler taken from the side opposite that shown in Fig. 1.

Fig. 3 is an end elevational view of the device of Fig. 1 as seen from one end thereof; and Fig. 4 is an end elevational view of the device as seen from the end opposite to the end shown in Fig. 3.

Fig. 5 is a top plan view of the device of Fig. 1; and Fig. 6 is a bottom plan view of the device.

Fig. 7 is a perspective view of the automobile cooler.

I claim:

The ornamental design for an automobile cooler, as shown.

THERON L. HEDGPETH.
